[57] **CLAIM**

The ornamental design for a toy collapsible structure, as shown and described.

DESCRIPTION

FIG. 1 is a front elevational view of a toy collapsible structure showing our new design;

FIG. 2 is a side perspective view thereof;

FIG. 3 is a view similar to FIG. 2 showing the other side perspective thereof; and,

FIG. 4 is a top plan view thereof.

The bottom and rear sides of the design are plain and unadorned.

FIG. 1

FIG. 2

FIG. 3

FIG. 4
